UNITED STATES PATENT OFFICE

2,000,072

ROAD MACHINE

Rudolph Gedstad, Peoria, Ill., assignor to Caterpillar Tractor Co., San Leandro, Calif., a corporation of California

Application February 2, 1933, Serial No. 654,863

8 Claims. (Cl. 37—110)

The present invention relates to road machines, and particularly to driving means for the carriers of elevating graders.

Elevating graders are used in earth moving jobs such as casting in from ditches, and building levees and the like where material is loaded at one place and conveyed by wagons or trucks to another location. As the machine moves forward the plow digs the earth and casts it on the lower end of an endless carrier belt which is supported on an inclined carrier frame and is driven to elevate the earth to the upper end of the carrier where it is discharged. In operation a continuous mass of material several inches deep and approximately a yard in width moves in a constant stream as the carrier belt is driven. When operation of the carrier belt is to be stopped, it is necessary to disengage the plow from the earth and allow the carrier belt to discharge all the material thereon so that when it has stopped no material remains on the belt to cause it to run backward. While this extra running of the carrier belt causes a loss of time and often extra work in elevating material which is not used, due to the fact that there is no wagon to receive it or that the elevating grader is making a turn, even more disadvantageous consequences are entailed if the conveyer is not cleared of material. This is true because the weight of material causes the carrier belt to run reversely and the mass of earth thereon is piled up around the lower end of the carrier and plow. This situation also occurs whenever the carrier belt is stopped unintentionally during operation. Such piling up of earth around the lower end of the carrier and the plow entails several undesirable results in that it is frequently necessary to remove the earth from around the carrier and plow before operation is resumed, and also due to the fact that earth often gets onto the lower stretch of the carrier belt clogging the rollers and often tearing the belt if operation is resumed before it is removed.

The present invention does away with the above disadvantageous features by providing a non-reversible drive for the carrier belt which is automatically locked against reverse movement. Thus in an elevating grader incorporating the invention disclosed herein, operation of the carrier belt can be stopped at any time without entailing undesirable consequences. No time is lost in clearing the carrier before stopping operation and no material is wasted while waiting for a wagon to be loaded or in making turns. Furthermore, whenever the carrier belt is stopped unin-

tentionally, it is automatically locked against reverse movement so that the material remains in position thereon and when repairs are completed and operation is resumed, no delay is encountered as would be the case if the carrier belt had run reversely and piled up material at the lower end of the carrier. A further advantageous feature is found in the invention disclosed herein in that the non-reversible means in the carrier belt can be disabled whenever it is desired to run the carrier belt in reverse direction, as, for instance, when repairing the belt at the splice or when removing the belt from the machine.

Statement of invention

It is an object of the invention to provide improved driving means for the carrier belt of an elevating carrier.

Another object of the invention is to provide an elevating grader in which operation of the carrier belt can be interrupted and resumed with no delay and no loss of earth dug by the plow.

Another object of the invention is the provision of irreversible driving means for the carrier belt of an elevating grader.

Another object of the invention is to provide an elevating grader having an endless carrier belt which is blocked automatically against reverse movement.

Another object of the invention is the provision of a brake for preventing reverse movement of the carrier belt of an elevating grader.

Another object of the invention is the provision of a brake for the carrier belt of an elevating grader which is adapted to lock the belt automatically against reverse movement, and which can be disabled at the will of the operator.

Another object of the invention is to provide driving means for the carrier belt of an elevating grader including irreversible means associated with a clutch-driven shaft.

Other objects will appear as the description progresses.

Description of figures

Figs. 1 and 2 are general views of the machine.

Fig. 1 is a rear elevation with a portion of the frame broken away.

Fig. 2 is a right side elevation with the carrier indicated diagrammatically.

Fig. 3 is a partial longitudinal vertical section illustrating the power unit.

Fig. 4 is a section on the line 4—4 in Fig. 3.

Fig. 5 is a plan view of the rear end of the machine with certain parts shown in section.

Fig. 6 is a view on the line 6—6 in Fig. 5.

Figs. 7-9 illustrate one form of the automatic locking brake.

Fig. 7 is a side elevation of a portion of the power unit with the brake shown in section.

Fig. 8 is an enlarged section of the brake.

Fig. 9 is a section on the line 9—9 in Fig. 8.

Figs. 10-12 illustrate a second form of the automatic locking brake.

Fig. 10 is a view on the line 10—10 in Fig. 6.

Fig. 11 is an enlarged view, partly in section, of the idler sprocket having the brake associated therewith.

Fig. 12 is a section on the line 12—12 in Fig. 11.

DESCRIPTION OF MECHANISM

Frame

The frame of the machine includes longitudinal channel 1, forming the left side frame member as viewed from the rear of the machine (Figs. 1 and 6), channels 2, 3 and 4 connected by a plurality of vertical posts 6 (Fig. 2) forming the right side frame member. Front cross channel 7 (Figs. 2 and 3) is secured to the front ends of channels 1 and 2, and rear cross channel 8 (Fig. 5) is secured to the rear ends of channels 1 and 4. Central cross channels 9 and 10 (Fig. 3) are connected at their left ends to longitudinal channel 1 and at their right ends to the inner ends of channels 2 and 4, respectively.

The front end of the frame is supported by similar forward extensions 11 (Figs. 2 and 3) which are secured to channels 7 and 9 and bend downwardly at their forward ends to rest on front wheel and axle assembly 12, indicated generally in Fig. 2. The rear end of the frame is supported in any suitable manner on rear wheel and axle assembly 13, indicated generally in Figs. 1 and 2. No detailed description of the wheel and axle assemblies will be given herein as they form no part of the instant invention. The frame members described above are interconnected by suitable braces.

Various auxiliary frameworks are mounted on the frame to provide supports for the adjusting mechanisms of the plow and carrier. Longitudinal framework 16 (Fig. 1) is mounted on the frame above channel 1 and provides a support for the plow adjusting mechanism. Transverse framework 17 (Figs. 1 and 3) rises from left side channel 1 to inner posts 6, said framework comprising spaced transverse sections substantially above respective central cross channels 9 and 10 (Fig. 3). Said framework 17 serves to support the carrier adjusting mechanism and the controls for the power unit.

Platform 18 is provided at the rear of the frame (Figs. 1 and 2) and forms an operator's station.

Plow and carrier

The plow assembly includes longitudinal plow frame channel 21 (Figs. 1 and 6) which carries plow 22 and is supported at each end from shaft 23 (Fig. 1) on framework 16 by chains 24, only one of which is seen in Fig. 1. Hand wheel 25 on shaft 23 provides a means for raising or lowering the plow which is provided with a suitable draft connection (not shown) to the front wheel and axle assembly. Connection 26 (Fig. 6) serves to determine the lateral adjustment of the plow with respect to the frame of the machine and the elevating carrier.

As described hereinbefore, the plow is adapted

to cast earth on the elevating carrier at the lower end thereof, and an endless carrier belt mounted on the carrier serves to elevate the earth and discharge it at the upper end of said carrier. The carrier assembly comprises upper carrier or section 31 (Fig. 1) and lower carrier or section 32 which are pivotally connected at 33. Each of said sections is provided with sideboards 34 to guide the material being elevated, said sideboards 34 being supported by brackets 35 from side frame members 36 which are connected by suitable braces.

Means are provided for adjusting lower carrier 32 to vary the position of said section with respect to the ground and to vary the inclination at which material is elevated. A pair of chains 37, only one of which is seen in Fig. 1, have their lower ends secured to opposite side members 36 of said lower section 32 and their upper ends secured to shaft 38 suitably mounted on framework 17 and provided with hand wheel 39 for winding or unwinding said chains 37 about said shaft 38 to raise or lower the lower carrier.

Means are provided for adjusting upper carrier 31 to vary the height at which the material is discharged. A pair of chains 41 (Fig. 1) are provided, only one of which is seen in Fig. 1, which are connected at one end to framework 17, pass over sheaves 42 suitably connected to opposite sides of upper carrier 31 adjacent the end thereof and have their other ends secured to shaft 43 which is provided with hand-wheel 44 and is mounted on said framework 17. By operating hand-wheel 44, the elevation of upper carrier 31 is adjusted to vary the height at which elevated material is discharged.

Means are provided for adjusting the carrier center to maintain equal inclinations of the upper and lower carrier sections. A pair of bars 46, only one of which is seen in Fig. 1, have their lower ends connected by a shaft which extends below the carrier adjacent pivotal connection 33, and said bars 46 engage suitable frame members to guide their movements. Said bars 46 are provided with racks adjacent their upper ends which are operated simultaneously by suitable gearing from shaft 47 mounted on framework 17 and having hand-wheel 48.

The endless carrier belt referred to hereinbefore is mounted on rollers in the carrier and is driven from the engine in a manner to be described hereinafter. Carrier belt 51 passes over driving drum 52 (Fig. 1) adjustably mounted in the outer end of upper carrier 31, idler rollers 53 (Figs. 1, 5 and 6) suitably journaled in side frame members 36, and larger idler roller 54 suitably journaled in the outer end of lower carrier 32. The idler rollers support the upper stretch of the carrier belt which is driven by drum 52 to elevate the earth cast thereon by the plow. The driving means for said drum 52 is described hereinafter.

Thus it is seen that the elevating carrier is adjustable at each end and at its center, being provided with an endless carrier belt adapted to elevate and discharge earth from the upper end of the carrier.

Power unit and carrier belt drive

The power unit comprises an engine having 70 crankcase 100 (Fig. 3), and clutch housing 101 bolted to the rear end of said crankcase. Cover 102 for said clutch housing 101 has an offset portion resting on and bolted to said cross channel 9 which forms a support for the rear end of the 75

power unit. The front end of the power unit is resiliently supported on front cross channel 7. Curved bracket 103 (Figs. 3 and 4) has its ends secured to crankcase 100 and the downwardly 5 curved central portion thereof rests on angle 104 which is secured to said channel 7. Bolt 106 has threaded engagement with said bracket 103 centrally thereof and extends downwardly through the aperture in the horizontal flange 10 of said angle 104, spring 107 being placed on said bolt between angle 104 and nut 108. Thus it is seen that a resilient front support is provided for the power unit which also permits a limited lateral oscillation thereof.

15 The drive for the carrier belt is transmitted from crankshaft 111 (Fig. 7) through clutch 112 to clutch driven shaft 113. Clutching and de-clutching of clutch 112 is controlled by similar arms 114, one of which is seen in Fig. 7, clamped 20 on shaft 115 and engaging opposite pins 116 on clutch thrust collar 117. Said shaft 115 is suitably journaled in clutch housing 101 and extends therethrough (Fig. 3). Arm 118 secured on shaft 115 outside of housing 101 has connection 119 with arm 120 secured on transverse shaft 121 suitably journaled in framework 17. Clutch control lever 122 provides a manually operable means for controlling clutching or declutching. Throttle control 123 for the engine is also suitably mounted 30 on framework 17.

The drive is transmitted from clutch driven shaft 113 through gear connection 130 (Fig. 7) to shaft 131 mounted in bearings 132, 133 in housing 101 and cover 102. Gear 134 mounted 35 on shaft 131 between said bearings 132, 133 meshes with gear 135 mounted on shaft 136, indicated in dotted lines. Said shaft 136 extends through cover 102 and has universal joint 137 with shaft 138 (Figs. 3 and 7) which is supported at 40 its rear end in housing 139 on frame bracket 141 secured to cross channel 10 (Figs. 5 and 6). Sprocket wheel 142 is mounted on shaft 138 adjacent the end thereof and chain 143 connects 45 said sprocket wheel 142 to larger sprocket wheel 144 on shaft 145 suitably journaled in housing 146 mounted on frame bracket 147. Smaller sprocket wheel 148 is also fast on said shaft 145 and through chain 149 indicated diagrammatically in Figs. 1, 5 and 6, drives sprocket wheel 151 50 (Fig. 1) fast on shaft 152 which carries carrier belt driving drum 52. Said chain 149 passes over suitable idlers 153 intermediate its length.

Means are provided for adjusting the tension 55 on sprocket chain 143 which connects sprocket wheels 142 and 144. Idler sprocket 156 (Fig. 6) engages said chain 143 and is oscillatable to vary the tension thereon. Said sprocket 156 (Fig. 10) has integral hub 157 which is rotatably mounted 60 on stub shaft 158 which is mounted in crank 159 having hub 160 engaging shaft 161 mounted in bracket 162 on frame bracket 141. Hub 160 has extension 163 to which hand lever 164 is riveted. It is seen, therefore, that by oscillating lever 164, sprocket wheel 156 is oscillated to vary the tension 65 on chain 143. Releasable means are provided for maintaining the sprocket wheel in adjusted position. Arcuate ratchet 166 is mounted on frame bracket 141 and pawl 167 (Fig. 10) slidably mounted on lever 164 is adapted to cooperate 70 therewith. Said pawl 167 is moved into or out of engagement with ratchet 166 by auxiliary handle 168 (Figs. 6 and 10) pivoted on said lever 164.

From the foregoing description it is seen that a controllable drive is provided for the carrier 75 belt.

As pointed out in the introduction, it is desirable that reverse movement of the carrier belt be eliminated and means are provided for preventing such reverse movement. An irreversible means in the form of an automatic locking brake 5 is associated with a clutch driven shaft. As illustrated in Fig. 8, shaft 131 projects beyond bearing 133, and the end thereof is housed in spacer 201 secured between clutch housing cover 102 and brake cover 202 by bolts 203, certain of which also 10 serve to maintain bearing retainer 204 in place. Within spacer 201, cam 206 (Figs. 8 and 9) is secured on shaft 131 by key 207 adjacent bearing 133 and said cam is provided with a plurality of offset cam surfaces 208 forming equally spaced 15 pockets between said cam and said spacer. It is to be noted that said pockets are deeper at one end than at the other. Said cam 206 is laterally positioned by spacers 209, which engage bearing 133, and nut 210 on said shaft 131, respectively. 20 As shown in Fig. 8, the circumferential portions of cam 206 are laterally rounded.

Braking elements are disposed within the pockets formed between the spacer and the cam which are adapted to lock said spacer and said 25 cam automatically against relative movement in one direction, while permitting relative movement therebetween in the opposite direction.

A roller 211 (Figs. 8 and 9) is provided in each 30 pocket and said rollers are of a diameter to permit rotation of the shaft 131 and cam 206 when disposed in the deepest portion of the pocket during clockwise rotation, in the direction indicated by the arrow in full lines in Fig. 9, but become wedged between cam surfaces 208 and spacer 201 35 upon rotation of said shaft 131 and cam 206 in a counter-clockwise direction, as indicated by the arrow in dotted lines in Fig. 9. Resilient means are provided for urging rollers 211 to locking position whenever clockwise rotation of said 40 shaft 131 and said cam 206 ceases. Plungers 212 (Fig. 9) are disposed in apertures formed in substantially radial portions 213 of said cam surfaces 208 and are integrally recessed to receive springs 214 which urge said plungers 212 outwardly 45 against rollers 211. During clockwise rotation of shaft 131, that is, when the carrier belt is being driven to elevate material, rollers 211 are forced against plungers 212, pushing them inwardly against the pressure of springs 214. However, if 50 such clockwise rotation ceases, or if counter-clockwise rotation ensues, plungers 212 urge rollers 211 to locking position where they are wedged between cam surfaces 208 and spacer 201, thus effectively preventing backward movement of the 55 carrier belt and the driving train therefor.

In a second form of the invention, an automatic locking brake is associated with idler sprocket 156. As shown in Fig. 11, sprocket hub 157 is mounted on bearings 221, 222 on shaft 158, 60 spacer 223 being interposed between said bearings. Fixed on shaft 158 to the right of bearing 222 is cam 226, similar to said cam 206, and positioned between spacers 227. The right hand spacer engages outer hub 228 of crank 159. The 65 entire assembly is secured on shaft 158 by nut 229 which holds washer 231 against bearing 221. Cover 232 is bolted to hub 157 closing the outer end, while seal 233 is seated within the inner end of sleeve 157 and engages hub 228. Cam 226 70 (Fig. 12) is provided with cam surfaces 234 similar to cam surfaces 208, forming pockets in which rollers 235 are positioned, said rollers being engaged by plungers 236 having springs 237 disposed therein. The operation of cam 226, rollers 235 75

and hub 157 is similar to that described in connection with cam 206, rollers 211 and spacer 201, except that in the latter instance cam 226 is stationary, rollers 235 permitting rotation of hub

5 157 in the direction of the arrow in full lines in Fig. 12, and preventing rotation thereof in the direction of the arrow in dotted lines.

Means are provided for disabling the irreversible means to permit backward movement of the 10 carrier belt when such movement is desired. As previously described, sprocket 156 and crank 159 are oscillatable about shaft 161 by means of hand lever 164 and when said sprocket 156 is completely disengaged from sprocket chain 143, the 15 carrier belt and the driving means therefor are free to move in a backward direction.

Thus it is seen that the driving means for the carrier belt includes irreversible means in the form of an automatic locking brake, which can 20 be disabled selectively according to the second form of the invention.

I, therefore, claim as my invention:

1. In an elevating grader, a frame, a carrier 25 adjustably supported in said frame, a carrier belt on said carrier, a motor mounted in said frame, a clutch housing, means for driving said belt from said motor including a clutch, a clutch-driven shaft, and means for preventing reverse movement of said belt comprising a cam 30 on said shaft having offset cam surfaces, a tubular member secured to said housing and surrounding said cam, said offset cam surfaces and the inner surface of said member forming pockets having substantially radial walls adjacent the 35 deeper ends thereof, rollers in said pockets, and spring-pressed plungers seated in said walls and engaging said rollers, said plungers serving to urge said rollers into engagement with said surfaces to lock said cam against reverse movement.

2. In an elevating grader, a frame, a carrier 40 adjustably supported in said frame, a carrier belt on said carrier, a motor mounted in said frame, a clutch housing, means for driving said belt from said motor including a clutch, a first clutch-driven shaft, a second clutch-driven shaft, a gear connection between said shafts, and means for preventing reverse movement of said belt comprising a cam on said second shaft having offset 45 cam surfaces, a tubular member secured to said housing and surrounding said cam, said offset cam surfaces and the inner surface of said member forming pockets having substantially radial walls adjacent the deeper ends thereof, rollers in 50 said pockets, and spring-pressed plungers seated in said walls and engaging said rollers, said plungers serving to urge said rollers into engagement with said surfaces to lock said cam against reverse movement.

3. In an elevating grader a frame, a carrier 55 adjustably supported in said frame, a carrier belt on said carrier, a motor mounted in said frame, a clutch housing, means for driving said belt from said motor including a clutch, a clutch-driven shaft, a bearing support for said shaft, and means for preventing reverse movement of said belt comprising a cam on said shaft adjacent said bearing support having offset cam surfaces, a tubular member secured to said housing and surrounding said cam, said offset cam surfaces and the inner surface of said member forming pockets having substantially radial walls adjacent the deeper ends thereof, rollers in 60 said pockets, and spring-pressed plungers seated in said walls and engaging said rollers, said plung-

ers serving to urge said rollers into engagement with said surfaces to lock said cam against reverse movement.

4. In an elevating grader, a frame, a carrier 5 adjustably supported in said frame, a carrier belt on said carrier, a motor mounted in said frame, a clutch housing, means for driving said belt from said motor including a clutch, a first clutch-driven shaft, a second clutch-driven shaft, a gear connection between said shafts, a bearing support for said second shaft, and means for preventing reverse movement of said belt comprising a cam on said second shaft adjacent said bearing support having offset cam surfaces, a tubular member secured to said housing and surrounding said cam, said offset cam surfaces and the inner surface of said member forming pockets having substantially radial walls adjacent the deeper ends thereof, rollers in said pockets, and spring-pressed plungers seated in said walls and 10 engaging said rollers, said plungers serving to urge said rollers into engagement with said surfaces to lock said cam against reverse movement.

5. In an elevating grader, a frame, a carrier 15 adjustably supported in said frame, a carrier belt on said carrier, a source of power, a clutch housing, means for driving said belt from said source of power including a clutch, a clutch-driven shaft, and means for preventing reverse movement of said belt comprising a cam on said 20 shaft having offset cam surfaces, a tubular member secured to said housing and surrounding said cam, said offset cam surfaces and the inner surface of said member forming pockets having substantially radial walls adjacent the deeper ends 25 thereof, rollers in said pockets, and spring-pressed plungers seated in said walls and engaging said rollers, said plungers serving to urge said rollers into engagement with said surfaces to lock said cam against reverse movement.

6. In an elevating grader, a frame, a carrier 30 adjustably supported in said frame, a carrier belt on said carrier, a source of power, a clutch housing, means for driving said belt from said source of power including a clutch, a first clutch-driven shaft, a second clutch-driven shaft, a gear connection between said shafts, and means for preventing reverse movement of said belt comprising a cam on said second shaft having offset 35 cam surfaces, a tubular member secured to said housing and surrounding said cam, said offset cam surfaces and the inner surface of said member forming pockets having substantially radial walls adjacent the deeper ends thereof, rollers in 40 said pockets, and spring-pressed plungers seated in said walls and engaging said rollers, said plungers serving to urge said rollers into engagement with said surfaces to lock said cam against reverse movement.

7. In an elevating grader, a frame, a carrier 45 adjustably supported from said frame, conveyor means on said carrier, a source of power, means for driving said conveyor means from said source of power including a clutch, a clutch-driven shaft, and means for preventing reverse movement of 50 said conveyor means comprising a cam on said shaft having offset cam surfaces, a stationary member surrounding said cam, said offset cam surfaces and the inner surface of said stationary member forming pockets, each pocket having a 55 deep end and a shallow end, and locking elements in said pockets, said elements being disposed in said deep ends during operative movement of said driving means and being adapted to wedge between said inner surface of said sta- 60

tionary member and said cam surfaces adjacent the shallow ends of said pockets upon reverse movement of said conveyor means.

8. In an elevating grader, a frame, a carrier 5 adjustably supported from said frame, conveyor means on said carrier, a source of power, means for driving said conveyor means from said source of power including a clutch, a clutch-driven shaft, and means for preventing reverse movement of said conveyor means comprising a member 10 rotatable with said shaft having offset cam surfaces, a stationary member surrounding said

rotatable member, said offset cam surfaces and the inner surface of said stationary member forming pockets, each pocket having a deep end and a shallow end, and locking elements in said pockets, said elements being disposed in said deep ends during operative movement of said driving means and being adapted to wedge between said inner surface of said stationary member and said cam surfaces adjacent the shallow ends of said pockets upon reverse movement of said conveyor means. 10

RUDOLPH GEDSTAD.
